(57) **CLAIM**

The ornamental design for the pylon design, as shown and described.

DESCRIPTION

FIG. 1 is an isometric view of the pylon design of this invention;

FIG. 2 is a front view thereof;

FIG. 3 is a rear view;

FIG. 4 is a right side view;

FIG. 5 is a left side view;

FIG. 6 is a top view; and,

FIG. 7 is a bottom view of the invention.

1 Claim, 1 Drawing Sheet

FIG. 1

FIG. 2

FIG. 3

FIG. 4

FIG. 5

FIG. 6

FIG. 7
